US00D755175S

(12) **United States Design Patent**
Bajwa et al.

(10) **Patent No.:** **US D755,175 S**
(45) **Date of Patent:** **** May 3, 2016**

(54) **INDUSTRIAL COMPUTER**

- (71) Applicant: **PHOENIX CONTACT
DEVELOPMENT AND
MANUFACTURING, INC.,**
Middletown, PA (US)
- (72) Inventors: **Jessbir Singh Bajwa**, Canton, MI (US);
Randal Earle Bradakis, Livonia, MI (US); **Russell Brink**, Ann Arbor, MI (US); **Patrick Kubovsky**, Mechanicsburg, PA (US); **Scott David Lindstrom**, Mechanicsburg, PA (US); **Michael Wayne Rothwell**, Mechanicsburg, PA (US); **Michael Ahlbrecht**, Bad Pyrmont (DE); **Sooshin Choi**, Cincinnati, OH (US); **Dietmar Knecht**, Leopoldshoehe (DE); **Stephen Dale May**, Lebanon, PA (US)
- (73) Assignee: **Phoenix Contact Development and Manufacturing, Inc.**, Middletown, PA (US)
- (**) Term: **15 Years**
- (21) Appl. No.: **29/545,355**
- (22) Filed: **Nov. 12, 2015**

(57) **CLAIM**

The ornamental design of an industrial computer, substantially as shown and described.

DESCRIPTION

FIG. 1 is a top view of an industrial computer;
FIG. 2 is a bottom view of the industrial computer shown in FIG. 1;
FIG. 3 is a front view thereof;
FIG. 4 is a rear view thereof;
FIG. 5 is a right side view thereof;
FIG. 6 is a left side view thereof; and,
FIG. 7 is a bottom right perspective view thereof.
The broken lines shown illustrate portions of the industrial computer that form no part of the claimed design.

1 Claim, 5 Drawing Sheets
